UNITED STATES PATENT OFFICE.

ARNOLD MOETTELLI, OF OBERWINTERTHUR, SWITZERLAND.

COOLING TOWER FOR DRY COOLING OF HOT COKE

Application filed December 28, 1921. Serial No. 525,520.

To all whom it may concern:

Be it known that I, ARNOLD MOETTELLI, a citizen of Switzerland, residing at and whose post-office address is Oberwinterthur, 5 Remerstrasse 21, Switzerland, have invented certain new and useful Improvements in Cooling Towers for Dry Cooling of Hot Coke, for which I have filed application in Switzerland, filed Jan. 3, 1921; Germany, filed June 20, 1921, of which the following is a specification.

The present invention relates to a cooling tower for dry cooling of hot coke, to which the latter is conveyed by means of buckets over a chute. The buckets effect automatically the removal of the mouth of the chute from the opening of the receptacle or chamber as well as the closing again of the cooling receptacle, by means of a lever actuated by said buckets during the charging operation and of a movable mouth piece of said chute connected with said lever and a sealing hood for the receptacle likewise connected with said lever, 15 while said buckets also effect the opening of the receptacle previous to dumping as well as the introducing of the mouth of said chute into the opening of the receptacle, and after the dumping is finished the removal of the mouth piece of said chute from the opening. By introducing the mouth piece of the chute into the opening of the receptacle the dumping height is reduced and in consequence a breaking of the 20 coke is prevented, and for the purpose of preventing the loss of heat the charging operation is accelerated on account of the automatic movements.

A mode of construction of the invention 25 is illustrated in the drawings.

a is a cooling chamber or receptacle for coke, known per se, having the charging opening *b* the discharge funnel *c* and the hood *d* closing the charging opening. *e* is 30 a bucket provided with rollers *f* which can be lifted by means of the hoisting device *g* along the rails *h* of U-shaped cross-section and bent at the top. While the lower rollers *f* run along the outside of the said 35 rails *h*, the upper rollers engage the recess of said rails.

i is a chute and *k* an extensible mouth-piece thereof. The latter is connected by means of the rope *l* to one end of the lever *n* pivoted at *m*, while the other end of the lever *n* is connected with the hood *d* by means of the rope *p* passing over the rollers *o*.

By means of the buckets *e* and the truck *q* the hot coke is conveyed from the distillation plant to the cooling tower. Then the said bucket is hoisted by means of the hoist *g* whereby the former meets the lever *n* close to its uppermost position. The lever is then turned to such an extent that it will lift the hood *d* from the cooling receptacle and cause the mouth-piece *k* of the chute to slide into the charging opening of the said cooling receptacle. During its further upward movement the bucket is tipped in known manner whereupon the coke will drop over the chute *i* and its extension piece *k* into the cooling chamber.

After the dumping is finished the bucket is again lowered on the truck *q* by the hoisting device. The lever *n* is thereby pushed back into its initial position simultaneously withdrawing the extension piece *k* of the chute from the opening *b* again and lowering the hood *d* until it again closes the charging opening *b*.

In order to obtain an air-tight seal of the chamber, the hood *d* drops into a circular channel containing a liquid and surrounding said opening *b*. If the pressure within the chamber increases the hood may be raised which instantaneously equalizes the pressure in the chamber and the outside air.

I claim:

1. A cooling tower for dry cooling hot coke comprising in combination a cooling chamber with a coke inlet, a bucket hoist and chute and means for opening and closing the inlet to the cooling chamber and at the same time bringing an extension mouth piece of the chute into and out of register with the cooling chamber inlet, said means being actuated by raising and lowering the bucket in the hoist.

2. A cooling tower for dry cooling hot coke comprising in combination a cooling chamber having an upper coke inlet covered

by a movable hood, a bucket hoist with tipping means and chute, a movable mouth piece in said chute, and a lever actuated by the bucket and connected to the hood and mouth piece so as to raise the hood and permit the movable mouth piece to slide into register with the cooling chamber inlet when a bucket is raised and to retract the

mouth piece and lower the hood when the bucket is lowered.

In testimony whereof I have affixed signature in presence of two witnesses,

ARNOLD MOETTELI.

Witnesses:

G. L. FRANK,
AUGUST QUIGG.
